UNITED STATES PATENT OFFICE.

WILBERT R. McGEE, OF SEATTLE, WASHINGTON.

CARTRIDGE-RELOADING MACHINE.

1,398,106.

Specification of Letters Patent.

Patented Nov. 22, 1921.

Application filed October 4, 1920. Serial No. 414,628.

To all whom it may concern:

Be it known that I, WILBERT R. McGEE, a citizen of the United States, residing at Seattle, in the county of King and State of Washington, have invented certain new and useful Improvements in Cartridge-Reloading Machines, of which the following is a specification.

This invention relates to machines for loading metallic-case cartridges.

The object of my invention is the provision of an inexpensively constructed machine of this character which will be convenient to use and capable of performing in an efficient and rapid manner.

The invention consists in the novel construction, arrangement and combination of parts as will be hereinafter described and claimed.

20 In the accompanying drawings, Figure 1 is a plan view of a cartridge reloading machine embodying the present invention. Figs. 2, 3 and 4 are detail sectional views through 2—2, 3—3 and 4—4 of Fig. 1. Fig. 5 is a front elevational view of the upper portion of the press member of the machine. Fig. 6 is a detail horizontal sectional view of a portion of the cartridge carrier and the locking block therefor, the locking block and 25 its housing being shown in plan. Fig. 7 is a sectional view taken substantially through 7—7 of Fig. 3.

In carrying out the invention, I provide a frame member having a circular cylindrical wall 10 and a top wall 11 upon which is mounted a wheel or carrier 12 rotatable about a post element 13 of the frame.

35 Adjacent to its circumference the carrier 12 is provided with a series of spaced holes 14 into which the cartridge cases are carried in vertical positions in the operation of the machine. 15 represents a shaft extending longitudinally through said frame and in front of the latter is provided with an 40 operating crank 16.

The shaft 15 has rigidly secured thereto an arm 17, Figs. 3 and 7 engageable with ratchet teeth 18 provided in the underside of the carrier to impart intermittent rotary 45 motion to the carrier in the direction indicated by arrow A, Fig. 1.

Also secured upon said shaft is a sleeve 19 having a peripheral cam ridge 20 engaging in a slot 21 of a chambered block 22 50 which is arranged to be reciprocated ra-

dially of the machine by such cam in a guideway 23 provided in the frame.

Formed or provided upon said block is a projection 24, Fig. 6, engageable in notches 25 provided in the carrier 12 whereby the latter is releasably secured in rotary positions suitable to accommodate the various functions of the machine. 26 represents a piston provided with a stem 27 adapted when a cartridge is brought into its C^o position, Fig. 3, to engage the same above the rim 28 at its closed end.

A spring 29 acting against piston 27 tends to retain the stem 27 at its outermost position for engaging cartridges of small diameters and yielding to accommodate those of larger size.

As shown in Figs. 1 and 2 the frame is provided with a receptacle 30 which is open at the top and of a width equal to the diameter of the largest cartridge for which the machine is intended.

The outer side 31 of said receptacle inclines outwardly as shown in Fig. 2. Within said receptacle is the arm 32 of a lever 30 which is fulcrumed at 33 and has its other arm 32¹ connected to a spring 34 tending to urge the arm 32 inwardly with respect to the machine. The lever arm 32 is desirably of the angular shape in which it is represented in Fig. 2 to furnish a seat at 35 for a case elevator 36 which is guided for vertical movements by ribs, such as 37 operating in ways such as 38 provided in the side walls of the receptacle. A lever fulcrumed to a stud 39 protruding from a hanger 40 within the machine frame has one of its arms 41 extended through a vertical slot 42 in the frame wall 10 into a slot provided in the elevator 36 and is operatively connected to 45 the latter by a pin 43 secured to the elevator and passing through a slot provided in the lever arm.

The other arm 41¹ of this lever is connected to an extensible spring 44 which acts 100 through the medium of the lever to raise the elevator for the purpose of hoisting a cartridge case into one of the carrier holes 14.

The elevator is restored to the normal position in which it is illustrated by means 105 of a cam 45 mounted on the shaft 15.

The elevator in being thus forced down bears against the lever arm 32 to cause the same to occupy the position in which it is illustrated.

A cartridge case C placed upon the elevator 36 in the receptacle 30 will in the upward travel of the elevator be swung by the lever arm 32 into vertical position to enable the case to be pushed into a hole 14 of the carrier. The form of the cam 45 is such that the elevator is not lowered from its highest position until in the progressive movement of the carrier the case is transferred thereby from the elevator to the top of the machine frame.

Included in the invention are devices for charging the cases successively with powder which will now be described with reference to Figs. 1 and 4. 46 represents a tubular column extending upwardly from the machine frame and having secured to a bracket 47 thereof a hopper 48 through which powder is supplied by gravity to a pressure equalizing compartment 49 whence it is delivered successively into two bottomless measuring cups 50 and 50¹.

These cups are revolved in a cylindrical compartment 51 so as to be brought alternately in alinement with the outlets 49¹ and 51¹ of the respective compartments to convey measured quantities of powder from the compartment 49 to a spout 52 whereby cartridge cases are successively supplied with powder charges when positioned below the spout as represented by C¹ in Fig. 4.

The cups 50, 50¹ are secured to the lower end of a vertical shaft 53 having secured to its upper end a star-wheel 54 (Fig. 1) 35 which is given intermittent rotary motion by a pinion 55 which is rotated continuously during the operation of the machine. More particularly the pinion 55 is provided with two arcuate surfaces 56 which fit within corresponding recesses 57 in the periphery of the star-wheel. The pinion is also provided with radially disposed projections 58 which successively engage against the arms of the star-wheel to impart rotary motion 40 thereto.

The pinion 55 is mounted on a stub shaft 59 which is driven by spur gears 60 from a shaft 61 extending through the column 46.

A shaft 62 connected to the shaft 61 by 50 bevel gears 63 and by bevel gears 64 to the operating shaft 15 serves to transmit motion to actuate the powder feeding devices explained above.

Subsequent to a case receiving its powder charge and when revolved in the carrier to a position denoted by C², a projectile P is manually inserted within the case.

The next and final step in the reloading of cartridges is to force the projectiles down 60 into the shells to predetermined distances.

This operation is accomplished by the press devices illustrated in Figs. 1, 3 and 5.

65 represents a crank arm secured to the rear end of shaft 15 and is operatively connected by a pitman 66 with a slide block

67 mounted for vertical reciprocatory motion in guideways 68 provided in the upper part of a support 69 which is rigid with the machine frame. The slide block carries at its front side an attachment 70 having at its lower end a conoidal recess, denoted by dotted lines 71 in Fig. 3, to receive the pointed end of the projectile. In each rotation of the shaft 15 the crank 65 thereof effects a downward movement to the block 67 and its attachment 70 to thereby force a projectile into a case, this pressing action occurs while the carrier 12 is held stationary by the lock 24 and while the case itself is engaged by the spring pressed stem 27.

The attachment 70 itself is secured to a block 72 which is slidable vertically in a slot 73 provided in the aforesaid slide block and is secured in adjusted position by a bolt 74 extending through a clamping plate 75 engageable against the back side of said slide block. The attachment is further secured against accidental displacement by means of a set screw 76 extending through a threaded hole in the slide block 67 to bear against the supplementary block 72.

To regulate the elevation to which the projectiles for any run of cartridges are to be brought, a standard cartridge placed in the carrier may be transported thereby into position occupied by cartridge C³ in Fig. 3 and desirably before powder is supplied to the hopper 48 therefor.

With the standard cartridge thus disposed and with slide block 67 in its lowest position the attachment 70 is independently lowered to seat upon the end of the projectile and secured as above explained.

After the cartridges have been loaded they are conveyed by the carrier to a position, as D, Fig. 1, whereat there is a recess—denoted by dotted lines 78—in the frame and through which the cartridges drop from the carrier.

To adapt the machine to different sizes of cartridge, it is necessary to employ a carrier having holes of suitable size, regulate the projectile press and, if requisite substitute powder measuring cups of the proper capacity for those being used.

The construction and operation of the invention will be understood, it is thought, from the foregoing description. Various changes, however, may be made with respect to the details of the hereinbefore described embodiment without sacrificing advantages of my invention and within the scope of the appended claims.

What I claim is,—

1. In a cartridge reloading machine, the combination with a rotary case-carrier, an operating shaft, and means actuated by the shaft for imparting intermittent rotary motion to said carrier, of a spring actuated case-elevator controlled by said shaft to automati-

cally supply cartridge cases to said carrier between the successive impulses of the carrier, tensioned means operated by said case elevator for receiving the cases in an inclined 5 position and shifting same to a vertical position for reception in the rotary case carrier, and devices actuated by the rotation of said shaft for releasably securing the carrier in positions to receive the cartridge cases.

10 2. In a cartridge reloading machine, the combination with a rotary case-carrier having a series of case-receiving openings, an operating shaft, and devices actuated by the rotation of said shaft to impart intermittent 15 rotary motion to said carrier, of means for inserting cartridge cases into the openings of said carrier between the successive movements of the latter, said means comprising a block guided for vertical movements, a lever 20 operatively connected to said block, a cam mounted upon said shaft, a spring connected to said lever, said cam and spring acting alternately to effect the vertical reciprocation of said block and a tensioned lever en- 25 gaged by said block coöperating with said block for shifting a case from an inclined position to a vertical position alined with the case receiving openings.

3. In a cartridge reloading machine, the 30 combination with a rotary case-carrier having a series of case-receiving openings, an operating shaft, and devices actuated by the rotation of said shaft to impart intermittent rotary motion to said carrier, of means for inserting cartridge cases into the openings 35 of said carrier between the successive movements of the latter, said means comprising a block guided for vertical movements, a lever operatively connected to said block, a 40 spring connected to said lever for actuating the same to elevate said block, a cam mounted upon said shaft for influencing said lever to effect the lowering of said block in opposition to said spring and a tensioned lever 45 engaged by said block coöperating with said block for shifting a case from an inclined position to a vertical position alined with the case receiving openings.

4. In a cartridge reloading machine, the 50 combination with a rotary case-carrier having a series of case-receiving openings, an operating shaft, and devices actuated by the rotation of said shaft to impart intermittent rotary motion to said carrier, of means for inserting cartridge cases into the openings 55 of said carrier between the successive movements of the latter, said means comprising a block guided for vertical movements, a lever operatively connected to said block, a spring 60 connected to said lever for actuating the same to elevate said block, a cam mounted upon said shaft for influencing said lever to effect the lowering of said block in opposition to said spring, and spring actuated 65 means rendered operative by said block in

the upward movements thereof for shifting the cases from inclined to vertical positions to enter into the respective carrier-openings.

5. In a cartridge reloading machine, the combination with a rotary case-carrier, an 70 operating shaft, and connections between said shaft and the carrier for intermittently impelling the carrier by an uninterrupted rotation of the shaft during the operation of the machine, of means for supplying 75 powder into cartridge cases carried by said carrier, said means comprising a hopper, a depending axially disposed spout therefor, revoluble measuring cups located between said hopper and the spout, a shaft carrying 80 said cups, a star wheel secured to the upper end of the shaft, a shaft driven by the operating shaft, a toothed pinion carried by the last named shaft in engagement with the star wheel, whereby the operating shaft is 85 caused to impart intermittent revolving motion to said cups whereby charges of powder are delivered to said cases between the successive movements of the carrier.

6. In a cartridge reloading machine, the 90 combination with a rotary case-carrier, an operating shaft, and connections between said shaft and the carrier for intermittently impelling the carrier by an uninterrupted rotation of the shaft during the operation 95 of the machine, of means for supplying powder into cartridge cases carried by said carrier, said means comprising a hopper, a spout, a pressure equalizing compartment intermediate said hopper and spout, revoluble measuring cups located between said compartments and the spout, a shaft carrying said cups, a star wheel secured to the upper end of the shaft, a shaft driven by the operating shaft, a toothed pinion 100 carried by the last named shaft in engagement with the star wheel, whereby the operating shaft is caused to impart intermittent revolving motion to said cups whereby charges of powder are delivered to said 110 cases between the successive movements of the carrier.

7. In a cartridge reloading machine, the combination with a rotary case-carrier, an operating shaft, and devices actuated by 115 said shaft to impart intermittent rotary motion to said carrier, of means to press projectiles into cartridge cases carried by said carrier between the successive movements of the carrier, means carried by the 120 machine and operated by said shaft to hold a cartridge case stationary when a projectile is placed therein, said first named means comprising a block guided for vertical movement, a projectile engaging attachment adjustably connected to said block, and operative connections between said block and the shaft whereby the rotation of the latter will effect vertical reciprocatory movements of said attachment and causing down- 130

ward movements of the same while said carrier is motionless.

8. In a cartridge reloading machine, the combination with a rotary case-carrier, an operating shaft, means actuated by said shaft to impart intermittent rotary motion to the carrier, and means operative between the successive impulses of the carrier for pressing projectiles into cases carried by the carrier, of devices actuated by said shaft for releasably locking said carrier during the operation of the last named means and means carried by said devices for resiliently engaging the cartridge case between rotary movements of the carrier.

9. In a cartridge reloading machine, the combination with a rotary case-carrier, an operating shaft, means actuated by said shaft to impart intermittent rotary motion to the carrier, and means operative between the successive impulses of the carrier for pressing projectiles into cases carried by the carrier, of devices actuated by said shaft for positively releasably locking said carrier,

and yielding means carried by said devices for engaging the cases successively when in position to have the projectiles forced there-in through the instrumentality of the projectile pressing means.

10. In a cartridge reloading machine, the combination with a rotary case-carrier, means for automatically feeding cases into said carrier, means to impart intermittent rotary motion to the carrier, means to press projectiles into the cases successively, means for resiliently engaging the cases when brought by the carrier into position below the projectile press means, and cam operated devices adapted to engage the carrier to hold the same against movement when a cartridge case receives a projectile.

Signed at Seattle, Washington, this 27th day of September 1920.

WILBERT R. McGEE.
